(57) **CLAIM**

The ornamental design for a bed, as shown and described.

DESCRIPTION

FIG. 1 is a top, right, front perspective view of a bed showing our new, original and ornamental design.

FIG. 2 is a front view of the bed shown in FIG. 1.

FIG. 3 is a side view of the bed shown in FIG. 1.

FIG. 4 is a top view of the bed shown in FIG. 1.

FIG. 5 is a cross-sectional view of the bed shown in FIG. 1 from the foot board to the head board showing the bed's width can vary; and,

FIG. 6 is a cross-sectional view of the bed shown in FIG. 1 from the side showing the bed's length can vary.

The broken lines are for environmental purposes only and form no part of the claimed design.
